Application April 26, 1952, Serial No. 284,545

10 Claims. (Cl. 200—114)

1

This invention relates to a cutout and load break switch for capacitor banks.

On power lines, it is frequently necessary to open the circuit for various reasons. Periodic inspection, timely adjustments or improved part installations means that the current must be shut off so that the lineman will be safe. It is also desirable to have a sturdy construction that can be opened again and again without damaging operative parts or blowing the fuse. I have devised a cutout and load break switch that as the door is opened, or a lever biased, a latch releases a fuse assembly allowing it to withdraw inwardly within a fibre fuse tube, thus breaking the circuit.

The primary object of this invention is to provide a cutout which operates as a drop-out fuse device under electrical overload and which also may be operated manually to open the circuit under load without damage to the apparatus.

Another object of this invention is to provide a cutout device in which the fuse link is not damaged when the device is manually operated under load and in which the fuse link can be re-established for further service after the device has been manually operated thus making it possible to open and close the fuse cutout as often as desired until the fuse link is ruptured by electrical overload.

Another object of this invention is to provide a cutout that has a fuse supporting casting attached to the porcelain housing by means of a fixed hinge, said fuse supporting casting having the leverage means of the cutout hinged and spring biased to it.

Another object of this invention is to provide a leverage construction which when operated, pivots around the fuse supporting casting and forces with its bias lower end the retaining latch downward to a point where it disengages a fuse link anchoring ferrule, freeing the entire fuse link assembly to spring upward into the fuse tube.

Another object of this invention is to provide a flexible cord attached to the lower end of the fuse link assembly to extend the spring in the fuse assembly to the point where the latch can be used to position the fuse assembly.

Other objects will appear from time to time in the course of the specification and claims.

Several embodiments of my invention are illustrated in the accompanying drawings, in which:

Fig. 1 is a side elevation with the housing broken away and part of the fuse assembly shown in section.

2

Fig. 2 is a section taken on the line 2—2 of Fig. 1.

Fig. 3 is similar to Fig. 1 showing a modified construction in the lower portion of the fuse assembly.

Fig. 4 is a section taken on the line 4—4 of Fig. 3.

Fig. 5 is a view of Fig. 1 showing the cutout after the door has been manually opened and the circuit opened.

Fig. 6 is a side elevation of my invention applied to an open type cutout and load break switch.

Fig. 7 is a fragmentary side elevation similar to Fig. 6 showing the latch open and the fuse assembly released.

This fuse cutout is designed to fit into one of the standard housings for closed or open cutouts made by the assignee of this invention. The closed cutout is shown in Figs. 1 and 3 and the open cutout in Figs. 6 and 7. The closed housing comprises a porcelain body portion 1 and a hinged door 2. On the side of the body portion 1 are openings 3 and 4 for entrance and exit of upper and lower terminals respectively. The door 2 has a handle eye 5 for the purpose of opening the door with a switch stick. The lower edge 6 of the door is cut diagonally downward toward the outer side at approximately a 45° angle, said diagonal edge 6 resting on a latch means.

The body portion 1 of the housing carries hook-like spaced portions 101 so as to removably seat a fuse supporting casting 7 by means of trunnions 3. The fuse supporting casting 7 extends diagonally upward and has a yoke portion 9 to loosely hold the fuse assembly 13. A tongue 10 extends upwardly from the yoke portion 9 of the fuse supporting casting 7 and serves to limit the movement of the door 2. Rods 11 extending to each side of the fuse supporting yoke 9 have U-shaped springs 12 pivoting around them to hold the door 2. One end of the U-spring is attached to the door at 14 and the other end of the U-spring is attached to the fuse supporting yoke at 15.

A latch 16 forms the lower contact means at the lower end of the fuse assembly 13, and is attached to the fuse supporting casting 7 by a hinge means 17. As can be seen in Fig. 2, the latch 16 has a straight leg portion 18 with a semi-circular portion 19 at the end opposite the hinge. A tongue 20 extends into this semi-circular portion 19 in a line with the straight leg portion 18. This tongue 20 is the means for holding a fuse anchoring ferrule 42 in closed circuit.

Resting on the latch 16 near its fulcrum so as to lessen the pressure is an arm 21. The outer end of this arm 21 has a tubular portion 22 to encompass the lower end of the fuse tube assembly 13 and to which it is attached by some pin means 23. The tubular portion 22 extends downwardly at 22a within the semi-circular portion 19 of the latch 16 leaving a space 24 between the sides of the semi-circular portion 19 and tubular extension 22a.

This tubular extension 22a has a slot 25 on one side to allow the tongue 20 of the latch 16 to pivot in and out. A bore within the tubular portion 22 has a shoulder 26 which on its upper side engages the fuse tube at 27 and on its under side provides a bevel 28 which in cooperation with the tongue 20 forms a means of holding the lower expanded end 29 of the fuse anchoring ferrule 42.

The fuse assembly 13 comprises a fibre tube 30 with an upper terminal 31 and a cap 32. This upper end of the fuse assembly is positioned by a spring arm 33 which notches downwardly at 34 to hold the cap 32. Fastened to the upper terminal 31 is a flexible leader 35 and an encompassing tension spring 36. The lower end of the tension spring 36 is secured to an internally threaded collar 37 constituting the lower terminal of the flexible leader 35.

The fuse unit itself is removable and comprises an upper cylindrical member 38 provided with a threaded stem 39 removably screwed into the member 37. A metallic sleeve 40 is flanged over the upper end of the member 38 and extends downwardly and has preferably a tight fit with a small fibre tube 41. A metallic ferrule 42 extends upwardly into the small fibre tube 41 and is slidable outwardly from said tube. It is held in place by means of the strain wire 43 and is also connected to the member 38 by means of the fuse wire 44. The anchoring ferrule 42 extends downwardly out of the lower end of the fuse tube 41 and at its lower end 29 fans out so as to engage the under side of the internal shoulder 26 of the extended tubular portion 22a at 29 as above described.

A flexible cord 45 or some similar holding means is secured to the expanded lower end portion 29 of the anchoring ferrule 42. This cord 45 can be used to extend the spring 36 to the point where the latch 16 can position the fuse assembly 13.

A conductive cable 102 can be attached to both the fuse supporting casting and the latch with sufficient loop to allow for the freedom of movement between the fuse supporting casting and the latch. This conductive cable assures a smoother flow of current between the said parts than is possible through a moving contact such as the hinge 11.

The variation of Fig. 3 is entirely in the shape of the latch 46 and the tubular member 47. The fuse anchoring ferrule 42 remains the same as in Fig. 1. The tubular member 47 terminates at its lower end on the upper surface of the latch 46 as shown in Fig. 3 whereas the corresponding tubular portion 22 as shown in Fig. 1 has an extension 22a below a like surface on latch 16. The latch 46 is a straight piece, hinged the same as in Fig. 1, with a hole 48 in line with the far side of the fuse assembly. To locate the fuse anchoring ferrule 42 and the latch, the fuse anchoring ferrule is pulled outwardly and somewhat toward the outer side of the fuse tube 30 by means of the flexible cord 45, until the ex-

panded anchoring ferrule end 29 is outside the tubular member 47. The latch 46 is then swung upwardly so that the hole 48 envelopes the expanded anchoring ferrule end 29 and a wedge action is performed on the said expanded anchoring ferrule end 29 by the side 48a of the hole 48 and the lower edge 47a of the tubular member 47.

The door of both Figs. 1 and 3 is shaped diagonally at the lower end 6. As the door is opened as can be seen in Fig. 5, it pivots around the pivot rod 11 by means of the U-shaped spring 12 which is fastened to both the door and the fuse supporting yoke 9. As the door pivots outwardly, the diagonal edge 6 biases downwardly the latch 16 of Fig. 1 or the latch 46 of Fig. 3. As the latch 16 moves downwardly as indicated by the dash dot lines the tongue 20 releases the fuse anchoring ferrule end 29 from under the shoulder 26 in Fig. 1. In Fig. 3, the latch 46 pivots downwardly on the pivot 11, and the wedging side 48a of the hole 48 swings away from the expanded end 29 of the fuse anchoring ferrule 42. This movement releases the anchoring ferrule end 42 so that the upward spring tension 25 of the spring 36 draws the inner fuse assembly upwardly in the fuse tube 30.

If overload should occur on the line, the fuse link 44 will blow and break the circuit. It will also release the fuse anchoring ferrule 42 so that it will drop down in the tubular portion 22 of Fig. 1 or the latch hole 48 of Fig. 3 to indicate that the fuse has blown.

My latch release of the inner fuse assembly can also be used on an open fuse cutout as shown in Figs. 6 and 7. The details of this cutout construction can be found in Reissue Patent No. 22,747 to William G. Schultz and Alwin G. Steinmayer and assigned to the same assignee as this application.

Generally, it consists of an elongated insulator 50 supported intermediate its ends in any suitable manner as by means of the clamp 51. The upper end of the insulator carries the upper terminal indicated generally at 52 and the lower end of the insulator carries a lower terminal indicated generally at 53. The upper and lower terminals are provided with apertures 54 for the reception of connectors and one or both of the terminals may be provided with a tie eyelet portion indicated at 55 for the upper terminal. The upper terminal extends outwardly and has an upwardly recessed portion 56 and a stop flange 57 rearwardly of said recessed portion. The lower terminal 53 is provided with a pair of hook like members 58 which are joined by means of a flange portion 59.

The cutout comprises a fuse tube 60 with an upper terminal 61 and a clamping cap 62 which fits into the recessed latching portion 56. The construction of the fuse tube is similar to that described for both Fig. 1 or Fig. 3, however, I illustrate the form of Fig. 1 in the lower portion.

The fuse supporting casting 63 is held by trunnion means 64 between the pair of hook like members 58. The fuse supporting casting 63 has a manipulating eyelet 65 on its inner side and a pivoting member 66 on its outer side. A U-shaped spring 67 extends around the pivot 66 and has one end attached at 68 to the fuse supporting casting 63 and the other end is attached at 69 to a lever means 70.

The lever 70 of Figs. 5 and 6 performs the same function as the door of Figs. 1 and 3. An eyelet portion 71 can be manipulated by a switch stick. The lower end of the lever 70 is shaped

diagonally at 72 so that as the lever 70 is pulled outwardly and pivoted on 66, the diagonal lower edge 72 will pivot inwardly and force the latch 16 downward on its pivot point 17 to the position shown in Fig. 7. The use and operation of my invention are as follows:

When an overload occurs the fuse link 44 and strain wire 43 are ruptured and the spring 36 draws the members 37 and 38 and the small fibre tube 41 upward in the main fuse tube 30. The fuse ferrule 42 is released and drops down and the latch 16 or 46 swings downwardly on its pivot 17 being biased in this direction by the pressure of the upper contact. After the latch 16 swings out of the way, the entire fuse assembly will drop to the position shown in Figs. 5 and 7. The protrusion of the fuse tube downwardly serves as a signal to linemen to notify them of a blown fuse. The entire assembly of door, fuse tube, fuse supporting casting and latch can be lifted off the hooks 16 and the blown fuse link removed and replaced by a new one.

If it is desired to open the cutout manually, it can be seen by referring to Figs. 5 and 7, that by pulling the door or a leverage means outwardly, it will pivot around projections from the yoke portion of the tube supporting casting. The diagonal lower edge 6 of the door will force the retaining latch downwardly to a point where it disengages the fuse link ferrule and the entire fuse link assembly will then be pulled upward into the tube by means of the biasing spring. This will open the circuit so that repair work or inspection can be performed.

It will be apparent that the cutout illustrated in each of the figures of the drawings is capable of breaking considerable load current when manually operated. This is made possible by release of the fuse link assembly 60 (Figs. 6 and 7) from its latching means 16 by action of the lower edge 72 of the lever means 70 as aforementioned, thus permitting the fuse anchoring ferrule end 29 of the anchoring ferrule 42 to separate from the contacting surface bevel 28 (Figs. 1 and 2). Said fuse anchoring ferrule end 29 then moves upward adjacent shoulder 26 of tubular portion 22 forming an arc between said ferrule end 29 and said shoulder 26 when said last mentioned conductive components are separated electrically by the lower end 27 of the fiber fuse tube 30. The arc is extended by further upward movement of the fuse link assembly 13 and is extinguished by non-ionized gas evolved from the interior surface of the fibre fuse tube 30.

When it is desired to close the cutout again, the fuse link assembly can be positioned by pulling the flexible cord 45 and extending the spring to the point where the latch can be used to position the assembly.

Thus, it can be seen that I provide an improvement in fuse cutouts which simplifies construction, reduces the number of parts, is rugged, gives protection from overload and can be opened manually again and again without damaging the fuse link assembly. It can be used on either the housed or open type cutout. When overload occurs, the fuse link breaks and the fuse tube drops down which signals the lineman that the fuse has blown. The fuse link can be replaced by a new one and the cutout is ready to go back into service. However, the fuse assembly is sufficiently sturdy so that the cutout can be opened manually innumerable times without causing damage or weakening to the vital parts.

I claim:

1. A fuse device comprising a fuse tube having an open end, a terminal at the opposite end of said fuse tube, a stationary contact normally connected to said terminal, a conductive tubular member adjacent the open end of said tube, a fuse link assembly normally electrically connecting said terminal and said tubular member, said fuse link assembly comprising a conductive leader and fuse section in series relation, a tension spring connected at its ends at points longitudinally spaced relative to said leader, and an anchoring ferrule adjacent the open end of said tube, said ferrule slidable inwardly of said tube under the bias of said spring, said anchoring ferrule normally electrically engaging said tubular member, and restraining means normally restraining said anchoring ferrule in contact with said tubular member and against inward movement in said tube and including releasing means for disengaging said restraining means of said ferrule.

2. A fuse cutout comprising a fuse tube having an open end, a terminal at the opposite end of said fuse tube, a stationary contact normally connected to said terminal, a hinge member having laterally spaced trunnions pivotally supporting said hinge member on bearing surfaces, said fuse tube slidably supported by said hinge member, a conductive tubular member carried by said tube adjacent the open end of said fuse tube, a pressure arm carried by and extending laterally from said conductive tubular member, a fuse link assembly normally electrically connecting said terminal and said tubular member, said fuse link assembly comprising a conductive leader and fuse section in series relation, a tension spring connected at its end at points longitudinally spaced relative to said leader, and an anchoring ferrule adjacent the open end of said tube, said ferrule slidable inwardly of said tube under the bias of said spring, said anchoring ferrule normally electrically engaging said tubular member, a latch pivotally connected to said hinge member and having a groove portion adjacent said tubular member, said latch being biased away from said tubular member by said pressure arm, a conductive portion on said tubular member extending therefrom and into said groove, the wall of said groove normally engaging said anchoring ferrule and holding it clamped to said vertical extension on the tubular member, and releasing means for disengaging said latch from said anchoring ferrule whereby the tension spring may retract the anchoring ferrule inward of said tube to open the electrical circuit.

3. A fuse cutout device comprising a fuse tube having an open end, a terminal at the opposite end of said fuse tube, a stationary contact normally connected to said terminal, a hinge member having laterally spaced trunnions pivotally supporting said hinge member on bearing surfaces, said fuse tube slidably supported by said hinge member, a conductive tubular member adjacent the open end of said fuse tube, a pressure arm carried by and laterally extending from said conductive tubular member, a fuse link assembly normally electrically connecting said terminal and said tubular member, said fuse link assembly comprising a conductive leader and fuse section in series relation, a tension spring connected at its ends at points longitudinally spaced relative to said leader, and an anchoring ferrule adjacent the open end of said tube, said ferrule slidable inwardly of said tube under the bias of said

spring, said anchoring ferrule normally electrically engaging said tubular member, a latch pivotally connected to said hinge member having a grooved portion adjacent said tubular member, said latch being biased away from said tubular member by said pressure arm, a conductive portion on said tubular member extending therefrom and into said groove, the wall of said groove normally engaging said anchoring ferrule and holding it clamped to said vertical extension on the tubular member, and releasing means for disengaging said latch from said ferrule comprising lever means pivotally mounted on said hinge member and normally biased against engagement with said latch whereby the latch can be urged about its pivot to disengagement with said anchoring ferrule permitting its retraction within the fuse tube to open the electrical circuit.

4. An enclosed fuse cutout comprising an insulating housing having an open bottom and front, a fuse tube having an open end adjacent said open bottom, a terminal at the opposite end of said fuse tube, a stationary contact normally connected to said terminal, a hinge member having laterally trunnions pivotally supporting said hinge member on bearing surfaces, said fuse tube slidably supported by said hinge member for movement through said open bottom, a conductive tubular member on said fuse tube adjacent said open end of said fuse tube, a pressure arm carried by and extending laterally from said conductive tubular member, a fuse link assembly normally electrically connecting said terminal and said tubular member, said fuse link assembly comprising a conductive leader and fuse section in series relation, a tension spring connected at its end at points longitudinally spaced relative to said leader, and an anchoring ferrule adjacent the open end of said tube, said ferrule slideable inwardly of said tube under the bias of said spring, said anchoring ferrule normally electrically engaging said tubular member, a latch pivotally connected to said hinge member adjacent said open bottom and having a grooved portion adjacent said tubular member, said latch being biased away from said open bottom by said pressure arm, a conductive portion on said tubular member extending therefrom and into said groove, the wall of said groove normally engaging said anchoring ferrule and holding it clamped to said vertical extension on the tubular member, and releasing means for disengaging said latch from said ferrule, said releasing means comprising an insulating door normally closing the front of said housing and pivotally supported intermediate its ends upon said hinge member, said door having its end adjacent said open bottom bevelled for wedge like engagement with and normally biased against engagement with said latch, hook engaging means on said door adjacent the other end thereof whereby the door may be manually pivoted to engage said bevelled end into engagement with the latch to release said anchoring ferrule allowing the tension spring to retract the anchoring ferrule inward of said tube to open the electrical circuit.

5. A fuse cutout comprising a fuse tube having an open end, a terminal at the opposite end of said fuse tube, a stationary contact normally connected to said terminal, a hinge member having laterally spaced trunnions pivotally supporting said hinge member on bearing surfaces, said fuse tube slidably supported on said hinge member, a conductive tubular member adjacent the open end of said fuse tube, a pressure arm

carried by and extending laterally from said conductive tubular member, a fuse link assembly normally electrically connecting said terminal and said tubular member, said fuse link assembly comprising a conductive leader and fuse section in series relation, a tension spring connected at its end at points longitudinally spaced relative to said leader, and an anchoring ferrule adjacent the open end of said tube, said ferrule slideable inwardly of said tube under the bias of said spring, said anchoring ferrule normally electrically connected to said tubular member, a latch pivotally connected to said hinge member and having a groove portion adjacent said tubular member, said latch being urged downward by said pressure arm and normally clamping said anchoring ferrule to said tubular member, releasing means for disengaging said latch from said ferrule and comprising an insulating lever means pivotally supported intermediate its ends upon said hinge member, one end of said lever means normally adjacent said latch and biased against engagement therewith, hook engaging means on said lever at the other end thereof whereby the lever means may be manually pivoted to engage said one end with the latch to release said anchoring ferrule on movement inward of said tube to open the electrical circuit.

6. A fuse device comprising a fuse tube having an open end, a terminal at the opposite end of said fuse tube, a stationary contact normally connected to said terminal, a hinge member having laterally spaced trunnions pivotally supporting said hinge member on bearing surfaces, said tube slidably supported on said hinge member, a conductive tubular member adjacent the open end of said fuse tube, a fuse link assembly normally electrically connecting said terminal and said tubular member, said fuse link assembly comprising a conductive leader and fuse section in series relation, a tension spring connected at its ends at points longitudinally spaced relative to said leader, and an anchoring ferrule adjacent the open end of said tube, said ferrule slideable inwardly of said tube under the bias of said spring, said anchoring ferrule normally electrically engaging said tubular member, and restraining means normally restraining said anchoring ferrule in contact with said tubular member and against inward movement in said tube and including releasing means for disengaging said restraining means from said fuse ferrule and comprising an insulating lever means pivotally supported intermediate its ends on said hinge member, said lever means normally biased against engagement with said restraining means and including manually engageable means whereby the lever means may be pivoted to bias the restraining means to release said anchoring ferrule for movement inwardly of said tube to open the electrical circuit.

7. A fuse device comprising a fuse tube having an open end, a terminal at the opposite end of said fuse tube, a stationary contact normally connected to said terminal, an insulator adjacent the open end of said fuse device, a supporting member carried by said insulator, a hinge member removably carried by said supporting member and slidably supporting said fuse tube, said hinge member engageable with a switch stick for dismounting said fuse device, a conductive tubular member adjacent the open end of said fuse tube, a fuse link assembly normally electrically connecting said terminal and said tubular member, said fuse link assembly com-

prising a conductive leader and fuse section in series relation, a tension spring connected at its end at points longitudinally spaced relative to said leader, and an anchoring ferrule adjacent the open end of said tube, said ferrule slideable inwardly of said tube under the bias of said spring, said anchoring ferrule normally electrically engaging said tubular member, restraining means normally restraining said anchoring ferrule in contact with said tubular member and against inward movement in said tube and including releasing means for disengaging said restraining means from said fuse ferrule.

8. A fuse device comprising a fuse tube having an open end, a terminal at the opposite end of said fuse tube, a stationary contact normally connected to said terminal, a hinge member having laterally spaced trunnions pivotally and removably supporting said hinge member on bearing surfaces, said fuse tube slidably supported by said hinge member, a conductive tubular member adjacent the open end of said fuse tube, a pressure arm carried by and extending laterally from said tubular member, a fuse link assembly normally electrically connecting said terminal and said tubular member, said fuse link assembly comprising a conductive leader and fuse section in series relation, a tension spring connected at its ends at points longitudinally spaced relative to said leader, and an anchoring ferrule adjacent the open end of said tube, said ferrule slideable inwardly of said tube under the bias of said spring, said anchoring ferrule normally electrically engaging said tubular member, a latch pivotally connected to said hinge member and having a groove portion for receiving a portion of said tubular member, said latch being biased away from said tubular member, a conductive portion on said tubular member extending therefrom and into said groove, the wall of said groove normally engaging said anchoring ferrule and holding it clamped to said conductive portion on said tubular member, and releasing means for disengaging said latch from said ferrule and comprising an insulating lever means pivotally supported intermediate its ends on said hinge member, said lever means normally biased against engagement with said latch, said lever means carrying switch-stick engaging means for removing said fuse device from said bearing surfaces and for pivoting said lever means to bias said latch to release said anchoring ferrule inward of said fuse tube to open the electrical circuit.

9. In a fuse device of the character described, a fuse assembly comprising a fuse tube having a

terminal at each end and open for expulsion at least one end thereof, a hinge member mounted on said tube for pivotally mounting said tube in said device, a fuse link in said tube normally electrically connecting said terminals and including a flexible conductor, a fusible section adjacent said open end and spring means biasing said fusible section toward the opposite end of said tube, said fuse link having a portion projecting from said open end, in combination with a clamping lever pivoted on said hinge member, and normally clamping the projecting end of said fuse link to the terminal at said open end, and a releasing lever pivoted on said hinge member intermediate its ends, one end of said releasing lever member juxtaposed to the swingable end of said clamping lever and the other end of said releasing lever having manually engageable means for pivoting said one end of said hinge member into pressure engagement with said clamping lever thereby to release said fuse link for withdrawal into said tube.

10. A fuse device comprising a fuse tube having an open end, a terminal at the opposite end of said fuse tube, a stationary contact normally connected to said terminal, a conductive tubular member adjacent the open end of said fuse tube and having interiorly thereof a shoulder adjacent its open end, said shoulder being bevelled to form a wedge-like portion extending outwardly relative to said tube, a fuse link assembly normally engaging said bevelled edge and electrically connecting said terminal and said tubular member, said fuse link assembly comprising a conductive leader and fuse section in series relation, a tension spring connected at its ends at points longitudinally spaced relative to said leader, and an anchoring ferrule adjacent the open end of said tube, slideable inwardly thereof under the bias of said spring, and having a cone-like portion normally electrically engaging said bevelled edge, and restraining means normally restraining said anchoring ferrule in contact with said edge and against inward movement in said tube and including releasing means for disengaging said restraining means from said fuse ferrule.

ALWIN G. STEINMAYER.
